HYDRAULIC TAPPET

Sidney Oldberg, Birmingham, Mich., assignor to
Eaton Manufacturing Company, Cleveland,
Ohio, a corporation of Ohio

Application July 23, 1949, Serial No. 106,413

5 Claims. (Cl. 123—90)

1

This invention relates to tappets for valve gear systems of internal combustion engines and more particularly to self-compensating hydraulic tappets of the self-contained variety.

Broadly the invention comprehends the provision of a self-contained, self-compensating hydraulic tappet comprising a hollow cylindrical body closed at one end and open at its other end, a plunger reciprocable in the body and providing therebetween a compression chamber, valve means for admitting fluid to and trapping same within the compression chamber and a flexible sleeve secured to the body upon its open end and to the plunger on one end thereof providing a substantially completely filled fluid reservoir therewith having communication with the compression chamber by way of the valve means, the ends of the sleeve being secured in a novel manner to the respective plunger and body to secure an effective holding thereto as well as inhibiting the leakage of fluid from the tappet per se.

Although numerous self-contained hydraulic tappets have been devised, none have proved entirely satisfactory both as to providing a feasibly economical structure and one that is effective in operation. The present structure is believed to answer the requirements sought primarily in the provision of a simple novel means for clamping the ends of a sealing sleeve to the relatively movable plunger and body of a self-contained hydraulic tappet effective to provide means for hermetically sealing hydraulic fluid in the tappet and for retaining the ends of the sleeve from relative movement or distortion from their sealing and holding positions.

An object of the invention is the provision of a self-contained hydraulic tappet that is relatively simple of construction and effective in operational use.

Another object of the invention is the provision of a hydraulic tappet containing its own fluid supply and operable to take up for the expansion or contraction of elements in a valve gear system in which it is employed having a sealing sleeve effectively secured at opposite ends to the basic plunger and body elements of the tappet for hermetically sealing the hydraulic fluid supply of the tappet therewithin so as to insure the continued operation of the tappet under all conditions to which it is subjected.

A further object of the invention is the provision of a self-compensating, hydraulic fluid supply self-contained tappet comprising basically a plunger, a body in which the plunger is reciprocable and normally biased outwardly therefrom by spring means, valve means controlling the flow

2

of fluid in one direction for the extension of the tappet and predetermined annular clearance between the plunger and tappet controlling the leak down flow of fluid between the reservoir and compression chambers of the tappet and a flexible sleeve connected at opposite ends thereof to the plunger and body enclosing the reservoir effective to hermetically seal a desirable hydraulic fluid of predetermined viscosity and operating properties in the tappet, said ends of the sleeve being held axially and radially from movement upon the respective plunger and body.

Other and further important objects and advantages of this invention will be apparent from the following description taken in connection with the drawings forming a part of the specification and in which:

Fig. 1 is a vertical partially cross-sectionalized view of a self-contained self-compensating hydraulic tappet;

Fig. 2 is a perspective view of the resilient sleeve diaphragm assembly for the tappet of Fig. 1;

Fig. 3 is an enlarged fragmentary vertical cross-sectional view of the valve mechanism for the tappet;

Fig. 4 is a horizontal cross-sectional view taken substantially along lines 4—4 of Fig. 3; and

Fig. 5 is a vertical cross-sectional view of a modified form of sleeve from that of Fig. 2.

The present self-contained self-compensating tappet was devised for the purpose of providing a mechanism which is relatively simple of construction and effective in operation incorporating therein in cooperation with the basic elements of structures of this sort a tube or sleeve member secured by clip members at the axial ends thereof into holding and sealing relation with the respective plunger and body of the tappet. The clip members are annular in form and provide a lip portion extending radially inwardly for end confining engagement of the extremities of the sleeve with which each clip is associated effective to resist movement or extension of the flexible tube therebeyond while the next adjacent portion is radially impressed into holding and sealing engagement on the respective plunger and body by an annular axial extended portion of the clip. The respective plunger and body are additionally provided, if necessary, to insure a more positive seal therein a plurality of annular grooves into which the inner annular portions of the sleeve engaging same are pressed.

The clip associated with the end of the sleeve engageable upon the plunger is arranged to have its radial lip pressed into an annular groove formed in the plunger, in addition to the other annular grooves therein, so as to provide a posi-

tive axial holding means between the sleeve and plunger in the relative movement thereof to the body in which the plunger is reciprocable.

The flexible sleeve in so being secured at its end extremities upon the plunger and body provides for the hermetic sealing of a hydraulic fluid completely filling the spaces provided between the plunger and body such that a reservoir or low pressure chamber is provided near one end of the plunger having valve controlled communication with a high pressure or compression chamber formed at the other end of the plunger between the plunger and body. In one form of sleeve made of rubber or similar resilient material the annular wall thereof extending between the secured ends thereof is of such strength and resiliency as to bear on the hydraulic fluid in the low compression chamber or reservoir with substantially atmospheric pressure when the plunger is extended a maximum amount relative to the body in which it is reciprocable and is capable of being distendable an amount radially outwardly sufficient to maintain a substantially constant volumetric space for the hydraulic fluid. This is essentially necessary for the proper function of the tappet in the displacement of fluid from one chamber to the other chamber in the operational extension and contraction of the tappet. The tappet, as shown by Fig. 1, is at its normal operating length and as such the plunger is relatively movable axially in both directions therefrom relative to the tappet body. A modified form of sleeve is made of fabric or similar substantially non-distendable material and as such is assembled on the plunger and body with the plunger bottomed thereby establishing its maximum volumetric holding capacity whereby upon the extension of the plunger it merely collapses inward radially with atmospheric pressure impressed on the fluid contained therein.

For the purpose of reducing servicing costs and making a self-contained self-compensating device that is adaptable to a plurality of different engines the device is embodied in a unit adaptable to insertion in a tappet body per se. As a service replacement unit it need thus be only necessary to lift the valve from off its seat to allow ample space to remove the faulty unit and replace same with a new one thereby alleviating the otherwise required tearing down or dismantling of the complete valve gear system.

Referring to the drawings for more specific details of the invention, 10 represents generally an automatic length compensating mechanism in the specific form of a tappet for use in a valve gear system of internal combustion engines effective to take up clearance therein automatically as same results to quiet the operation thereof. The tappet comprises a cylindrical tappet body 12 open at one end and closed at its other end providing a cavity 14 therein adapted to receive an automatic length compensating self-contained unit 16 therein.

The unit 16 comprises a cylindrical body 18 closed at one end and open at its other end providing a cavity 20 therein in which a plunger member 22 is reciprocable. The external surface of the body 18 is provided with an annular rib 24, one axial end of which bears upon the axial extremity of the tappet body 12 with the closed end of the body 18 pressed or otherwise suitably received in cavity 14 of body 12.

The tappet body 12 is adapted to be received in a tappet guide, not shown, for reciprocable movement therein and has welded or otherwise suit-

ably secured at its closed end a mushroom-shaped head 26 adapted to be engaged by an engine cam member or the like, not shown.

The plunger member 22 includes an annular reduced portion 28 of lesser diameter than head portion 30 and body portion 32, axially spaced therebetween, the purpose of which will herein-after appear and provides fluid passage 34 therethrough extending centrally through the body portion 32 into connection with the reduced annular portion 28. The passage 34 is adapted to communicate with a high pressure or compression chamber 36 formed between the end extremity of body portion 32 of the plunger and closed inner end of body 18 controlled as by a disc valve 38 adapted to be positioned on valve seat 40 provided at the terminus of passage 34 in chamber 36. The valve seat and valve 38 are so cooperably shaped as to provide for solely annular line sealing contact therebetween thereby assuring an effective seal and valve 38 is limited in its radial and axial movements respectively by an annular enclosure 41 forming a part of body portion 32 of plunger 22 having a plurality of radial slots therein for free passage of fluid therethrough and a coil spring 42 the end coil of which bears in overlapping relation on enclosure 41 so as to limit the movement of the valve axially therefrom. The spring 42 which is interposed in compression chamber 36 between the inner closed end of body 18 and the enclosure 41 serves to normally bias the plunger outwardly of the body 18 and by providing for slight clamping or holding of the end coils respectively on the plunger and body the spring acts as a rotation prevention means between the plunger and body so as to prevent the possible distortion or twisting of rubber which might tend to injure or destroy its function.

40 The head portion 30 of plunger 22 is coupled to the open end of body 18 by a resilient rubber or like material sleeve 44 secured therebetween one end of which is held in pressed sealing relation upon the exterior surface of body 18 near its open end by an annular clip member 46 secured upon one end extremity of the sleeve. The clip 46 provides a lip portion 48 inwardly radially extended and turned back axially on itself having a portion of the end of the sleeve annularly clamped therein such that it can not be extended axially therefrom and an axial annular portion 50 bearing annularly externally of the sleeve near its one extremity effective to cause a radial bearing in sealing engagement of the inner wall of the sleeve on the external surface of the body 18. The clip 46 for the purpose of stiffening or reinforcing same is provided with a rib or annular turned end 52 at its annular end disposed away from lip 48. The curved section of lip portion 48 of clip 46 in its clamping position on the one end extremity of sleeve 44 and with the clip and sleeve assembled on the external surface of the body 18 abuts the upper axial shoulder of annular rib 24, thus positively inhibiting the axial movement of the sleeve and clip in one direction on the body 18.

50 A clip 54 similar to clip 46 but of a size to conform with the size of sleeve 44 at end 56 thereof and head portion 30 upon which end 56 of sleeve 44 is to be secured is clamped upon end 56 of sleeve 44 and is provided with portions 58, 60 and 62 corresponding in structure and purpose to the portions 48, 50 and 52 of clip 46. The lip 58 of clip 54 serves at its extremity to positively inhibit the axial movement of end 56 of the sleeve

70 75

from movement relative to head 30 of the plunger during the reciprocation thereof by its receipt in an annular groove 64 formed on the external surface of head 30.

The external surfaces of the respective plunger 22 and body 18 upon which the respective ends of the sleeve 44 are pressed for sealing and holding engagement are provided with a plurality of parallel grooves 66 into which portions of the sleeve are pressed to insure an effective sealing and holding thereon.

The sleeve 44 in extending between the head 30 of the plunger and external surface of the body 18 provides in conjunction with the annular reduced portion of plunger member 22 a low pressure chamber or reservoir 68 having communication by way of passage 34 with compression chamber 36.

The body portion of plunger 22 is of a diameter slightly smaller than the diameter of cavity 20 permitting of a predetermined hydraulic fluid leakage or leakdown along the corresponding walls thereof between the low and high pressure chambers, 68 and 36 respectively.

It has been generally determined for the best operation of the tappet under all conditions to which it is to be subjected that a fluid should be employed permitting of a wide range of temperature use without much effect therein as to viscosity and the like and one permitting of a reasonable degree of machining tolerances of the parts thereof so as to provide for a structure that may be economically manufactured.

Fig. 5 illustrates a modified form of tube or sleeve 100 from that employed in the structure of Fig. 1 adaptable for use similarly to sleeve 44 between plunger 22 and cylindrical body 16.

Sleeve 100 terminates in opposite extremities 102 and 104 respectively upon which are clamped clip members 106 and 108 respectively, said clip members adapted to serve a like purpose as the clips 46 and 54 clamped to sleeve 44. The sleeve 100 is preferably made of a fabric material of substantially non-resilient character folded over at point 110 such that end extremity 102 thereof extends in the same direction as extremity 104 with said end 102 disposed radially inwardly of the main body portion 112 of the sleeve.

The sleeve 100 as shown by Fig. 5 is in its maximum contracted length as it would appear at the time of bottoming of plunger 22 relative to body 16 whereby upon elongation of the tappet per se and movement of the plunger from the body with the sleeve disposed between the plunger and body the sleeve would become elongated. It will be observed that because of the assembled size of the sleeve 100 at its minimum length it would be at its maximum volumetric holding capacity thereby establishing a condition wherein no appreciable pressure other than atmospheric is impressed upon the fluid contained in the reservoir of the tappet by the sleeve.

As the tappet elongates and the sleeve is lengthened axially the main body portion of the sleeve collapses or moves radially inwardly induced by atmospheric pressure externally thereof as compared to the slight vacuum created internally of the sleeve brought about through the movement of the fluid from the reservoir to the high compression chamber of the tappet as the tappet is elongated through the biasing apart of the plunger from the body by spring 42. In this manner the sleeve operates to maintain the volume internally of the tappet constant without im-

posing a resilient load of varying degree to the fluid.

The sleeve 44 differs from the sleeve 100 in the fact that because of its resilient nature it can be assembled to the plunger and body at normal operating length of the tappet in a slightly outwardly radial distention as the plunger is bottomed and approaching normal static axial length and zero distention when the tappet is elongated to its maximum height.

Aside from the hereinbefore recited comparison of actuation of the sleeves 44 and 100 the tappet per se 10 would be operable comparably through the use of either sleeve and that is, upon requirement for an elongation thereof or relative movement of the plunger 22 outwardly from the body 16 to compensate for clearance in a valve gear or like system in which it is employed fluid flows from chamber 68 through the passages 34 in the plunger and past valve 38 into chamber 36. This fluid flow action is caused by the creation of a slight vacuum in chamber 36 through the outward movement of the end of the plunger therein causing an enlargement of the volume of chamber 36 which in turn necessitates the requirement for more fluid to fill same. Simultaneously as chamber 36 increases in volume chamber 68 decreases in volume through the atmospheric pressure imposed upon the sleeve externally thereof and the normal resiliency of say sleeve 44 tending to move the fluid from chamber 68 or the atmospheric pressure solely acting externally in the case of use of sleeve 100.

In the case of either sleeve 44 or sleeve 100 it is of vital importance that the clips secured thereon at the end extremities thereof effect a positive hermetic seal upon the plunger and body inhibiting the leakage of fluid from the tappet or seepage of air into the tappet.

With the provision of a predetermined clearance between the outer periphery of the plunger and wall of cavity 20 in body 16 a predetermined rate of leakage between chambers 36 and 68 is provided permitting of the contraction of the tappet, that is inward axial movement of the plunger toward the bottom of cavity 20 in cylinder 16 against the resistance of spring 42 and rate of flow of fluid from chamber 36 to chamber 68 along the wall clearance space.

As the fluid flows from chamber 36 into chamber 68 the volumes of the chambers vary, chamber 68 increasing in volume as chamber 36 decreases such that in the case of sleeve 44 and because of its inherent resiliency it is distended slightly radially outward to compensate for the increase in volume of chamber 68 during this phase of operation of the tappet. The sleeve 100 because of its substantially non-resilient structure and mode of application to the tappet upon the contraction thereof substantially resumes its maximum volumetric carrying capacity such as shown by Fig. 5 wherein the fluid capacity of the sleeve in association with the plunger and body is increased.

Aside from the difference in resiliency of the materials from which sleeves 44 and 100 are made accounting for the slight variation in operating characteristics to one another the basic function of the sleeves is identical to that of providing an effective sealing of the fluid within the internal confines of the sleeve and cylinder body and for providing volume variation compensating means in the chamber disposed intermediate the plunger and sleeve whereby substantially only atmos-

spheric pressure is imposed at all times on the fluid of said chamber.

While this invention has been described in connection with certain specific embodiments, the principle involved is susceptible of numerous other applications that will readily occur to persons skilled in the art. The invention, therefore, is limited only as indicated by the scope of the appended claims.

What I claim is:

1. In a lash take-up device for valve gear and the like, a hollow cylinder closed at one end, a plunger slidable in said cylinder and projecting outwardly of the open end thereof, a passageway through said plunger communicating at one end thereof with the chamber defined by the inner end of said plunger and the closed end of said cylinder, said plunger having an axial recess at its inner end, the bottom of said recess defining an annular valve seat around the inner end of said passageway, a one-way valve on the valve seat in the recess of said plunger, a counterbore in said recess defining an annular axially facing shoulder, a spring in said chamber, having one end seated against said shoulder, urging said plunger outwardly of said cylinder, the axial distance from said seat to said shoulder being greater than the thickness of said valve, the inside diameter of said one end of said compression spring being less than the diameter of said valve whereby said spring retains said valve in said recess in proximity to said valve seat, a flexible tubular sleeve surrounding and clamped at one end to the outer surface of said cylinder adjacent the open end thereof and clamped at its other end to the projecting portion of said plunger, said plunger, cylinder end, and sleeve defining a reservoir therebetween, said passageway communicating at its other end with said reservoir, the means for clamping said sleeve to said cylinder and plunger comprising, annular metallic clips each having an inner and outer annular portion between which the ends of the sleeve are clamped, the said inner annular portions snugly embracing the said cylinder and plunger, respectively, each of said outer annular portions extending axially inwardly of the ends of said sleeve beyond the corresponding ends of said inner annular portions and being resiliently biased at their inner ends to press said sleeve radially inwardly, and circumferential grooves around said cylinder and plunger, respectively, radially inwardly of the said inner ends of said outer annular portions whereby said resilient outer annular portions press said flexible sleeve into said grooves to effect a liquid-tight seal between said sleeve and said cylinder and plunger.

2. In a lash take-up device for valve gear and the like, a hollow cylinder closed at one end, a plunger slidable in said cylinder, a passageway through said plunger communicating at one end thereof with a chamber defined by the inner end of said plunger and the closed end of said cylinder, said plunger having an axial recess at its inner end, the bottom of said recess defining an annular valve seat around the inner end of said passageway, a disc valve element in said recess and engageable with said valve seat, a counterbore in said recess defining an annular axially facing shoulder, a compression spring seated at one end against said shoulder and bearing at its other end against the closed end of said cylinder, the axial distance from said valve seat to said shoulder being greater than the thickness of said valve disc, the inside diameter of said one end of said compression spring be-

ing less than the diameter of said valve disc whereby said spring retains said disc in said recess in proximity to said valve seat.

3. A device as defined in claim 2 wherein the peripheral wall of said recess is provided with radial slots extending axially inwardly beyond said shoulder to provide passageways for fluid.

4. In a lash take-up device for valve gear and the like, a hollow cylinder closed at one end, a plunger slidable in said cylinder, a passageway through said plunger communicating at one end thereof with a chamber defined by the inner ends of said cylinder and plunger, said plunger having a centrally located axial recess at its inner end, with the bottom of said recess defining an annular valve seat around the inner end of said passageway, a flat valve element received in and movable in said recess and engageable with said valve seat, said recess being of an axial length greater than the thickness of the valve, a compression spring in said chamber urging the plunger outwardly of the cylinder, having one axial end bearing against the inner closed end of the cylinder and its other end bearing against the inner end of the plunger adjacent to the recess, with a portion of said one end of the spring inward radially overhanging the recess, the inside diameter of said one end of the spring being less than the maximum width of the valve element whereby said spring retains said valve element in said recess in proximity to said valve seat.

5. In a lash take-up device for valve gear and the like, a hollow cylinder closed at one end, a plunger slidable in said cylinder and projecting outwardly of the open end thereof, a passageway through said plunger communicating at one end thereof with the chamber defined by the inner end of said plunger and the closed end of said cylinder, said plunger having an axial recess at its inner end, the bottom of said recess defining an annular valve seat around the inner end of said passageway, a one-way valve on the valve seat in the recess of said plunger, a counterbore in said recess defining an annular axially facing shoulder, a spring in said chamber, having one end seated against said shoulder, urging said plunger outwardly of said cylinder, the axial distance from said seat to said shoulder being greater than the thickness of said valve, the inside diameter of said one end of said compression spring being less than the diameter of said valve whereby said spring retains said valve in said recess in proximity to said valve seat, a flexible tubular sleeve surrounding and clamped at one end to the outer surface of said cylinder adjacent the open end thereof and clamped at its other end to the projecting portion of said plunger, said plunger, cylinder end, and sleeve defining a reservoir therebetween, and said passageway communicating at its other end with said reservoir.
